ALFRED E. WATTS, OF

SWIMMING-INSTRUCTION MACHINE.

1,316,524.

Specification of Letters Patent. Patented Sept. 16, 1919.

Application filed July 27, 1918. Serial No. 247,042.

To all whom it may concern:

Be it known that I, ALFRED E. WATTS, a citizen of the United States, residing at Duluth, in the county of St. Louis and State of Minnesota, have invented certain new and useful Improvements in Swimming-Instruction Machines, of which I do hereby declare the following to be a specification.

My invention relates to swimming instruction apparatus and has for its object the provision of apparatus to be used on land for forcing the student through the movements of swimming, moving his arms and legs in perfect unison and in such manner and at such times with relation to each other, and with such repetition as to impress upon his mind a correct knowledge of the operation, and to create or develop in the student a tendency to unhesitatingly employ such movements when he enters the water, as a result of which he will accomplish the act of swimming. My invention is particularly adapted to teach the movements employed in the well-known breast-stroke style of swimming, wherein the swimmer lies breast downward and extends his arms and hands forwardly from points near his shoulders, sweeping them at full length from the forward position laterally and backward, at the same time drawing up his knees and kicking backwardly. With this, and other objects in view, my invention consists of the constructions, combinations and arrangements of parts hereinafter described and claimed.

In the drawings, Figure 1, is a perspective view of a machine embodying my invention, showing the movable parts thereof at the position corresponding to the position of the student's fully extended arms when nearly at the limit of their lateral and backward sweep. Fig. 2 is a central vertical longitudinal section of said machine showing the moving parts thereof in approximately the same position as in Fig. 1. Fig. 3 is an enlarged top plan view of a portion of one side of said machine, showing one of the herein-after described arm operators in the position corresponding to the beginning of the student's arm stroke. Fig. 4, is a view similar to Fig. 3, except that said arm operator is shown in the position corresponding to the position of the student's arm when fully extended and moved only a short distance along its lateral and backward path from its farthest forward position. Fig. 5 is a frag-

mentary vertical section on the line A—B of Fig. 3. Fig. 6 is a fragmentary vertical section on the line C—D of Fig. 3. Fig. 7 is a detail perspective view of the herein-after described spring-coupled blocks or carriage, shown in the position corresponding to Figs. 3, 5 and 6. Fig. 8 is a fragmentary plan view showing portions of the herein-after described power transmission gear. Fig. 9 is a plan view of a modified form of carriage which may, if desired, be employed instead of the form or structure shown in Fig. 7. Fig. 10 is an end view of said modified form. Fig. 11 is a transverse section of said modified form of said carriage supporting arm, on the line E—F, of Fig. 9. Fig. 12 is a side elevation of said modified form of carriage and arm. Fig. 13 is a side elevation of said modified form of carriage and arm, showing a modified form of track rail which may be employed instead of the form of herein-after described track rail shown in Figs. 3, 5 and 6. Fig. 14 is an end view of the herein-after described guide or track wheel adapted to run on said modified form of track, and of a portion of the track rail on which it runs.

In the drawings, 1 is a frame of any suitable construction, whereon is mounted a rotatable main power shaft 2, which said shaft may be rotated by any suitable means, as by a motor 2^a, and a worm 2^b driven by said motor and engaging a worm wheel 2^c mounted on said shaft and adapted to turn therewith; or, if preferred, said shaft may be manually rotated by means of a crank 2^d. Said shaft is provided with journal boxes of any suitable number or construction as 2^e. Mounted upon one end of said shaft is a gear 2^f. Mounted in bearings of any suitable construction secured to said frame is a transversely-directed rotatable transmission shaft 3, upon which is mounted a gear 3^a adapted to rotate therewith and to engage and be driven by said gear 2^f. Said shaft 3 is provided with a crank 3^b of any suitable construction whereby power from said shaft 3 may be transmitted through a connecting rod 4 to a rock bar or lever 5 mounted upon said frame. Upon said shaft 3 are also mounted gears 3^c and 3^d adapted to turn with said shaft 3; said gear 3^c being adapted to engage and turn a gear 6^a mounted upon a vertical shaft 6 and adapted to turn therewith, and said gear 3^d being adapted to engage a gear 7^a mounted upon

a vertical shaft 7 and adapted to turn therewith, the construction and arrangement of parts being such that the shafts 6 and 7 turn in opposite directions with respect to each other. Upon the upper ends of said shafts 6 and 7 are mounted certain mechanisms which in co-operation with hereinafter described guides operate as arm and hand controls. Since the mechanisms mounted upon said shaft 6 are for operating the student's left arm and hand and correspond to the mechanisms mounted upon said shaft 7 for operating the student's right arm and hand, it is not believed necessary to describe the left arm mechanism further than to say that the left arm mechanism operates in unison with the right arm mechanism in an opposite direction.

Upon the upper end of said shaft 7 is preferably mounted a transverse or radially-directed guide of any suitable structure, as sleeves 7^b, which guide is adapted to turn with said shaft 7, and which guide engages and supports a reciprocable arm or lever 8 of any suitable construction. Mounted upon the outer end of said lever is a carriage of any suitable construction preferably comprising a rigidly mounted block 8^a and intermediate of said block and said guide 7^b a slidable block 8^b, which blocks are coupled together by any suitable tension means which will tend to draw them together but permit them to separate a limited distance, as by one or more springs 8^c. Depending from said block 8^a is a guide wheel 8^d, and depending from said block 8^b is a guide wheel 8^e of any suitable form or structure. Said guide wheels are adapted to engage respectively the outer and inner sides of an approximately elliptical track or cam rail 9, which track follows a course corresponding to the course followed in the breast stroke by a swimmer's right hand. Said track is supported on said frame in any suitable manner, as by a spider 9^a. Said track surrounds said guide 7^b longitudinally thereof, and it will thus be apparent that since said guide 7^b rotates with said shaft 7 said blocks 8^a and 8^b will, by means of the reciprocable arm or lever 8, be swung in a plane parallel to said track, and by means of said guide wheels 8^d and 8^e, will be held in courses parallel to the course of said rail 9. Erected upon either of said blocks 8^a or 8^b, is a pin 10 which is stationary with respect to the block upon which it is erected. Mounted upon the forward end of said frame 1 is a centrally positioned longitudinally extending guide rod 11 upon which is mounted a slidable block 12 in which block is fixed one or more transversely disposed guide rods 13 extending on each side of said block at right angles to said rod 11 and above said track 9. Mounted upon said pin 10 is a guide follower of any suitable structure adapted to

engage said guide 13, as a guide wheel 14 interposed between the parallel rods 13, whereby the movement of the spring-coupled blocks and pin 10 around the course of said rail 9 will be translated into a reciprocating movement of the block 12 along said rod 11. Mounted upon said rod or rods 13 is a reciprocable base plate 15 provided at its end nearest said block 12, with an eye engaging said pin 10, by which the motion of the spring-coupled blocks parallel to the course of said rail is translated into a reciprocating movement of said base plate along said rod or rods 13. Loosely mounted upon said pin 10 is a table 16 through which said pin extends, and positioned at one end of said table is a hand rest 17 hinged at one side by means of a hinge rod 16^a to said table 16. Extending at the same end but opposite side from said table 16 is a lip 16^b adapted to limit the drop of the free side of said hand rest. Mounted upon said hand rest are shallow bridges 17^a and 17^b secured to which bridges and extending across said hand rest is a hand retaining strip 17^c, of any suitable material.

In order to oscillate said table 16 on said pin 10 so as to keep said hand rest in line with the student's forearm at all times without muscular effort, said table is provided at its opposite end with a lever 16^c, to which is connected one end of a bell crank lever 18, the opposite end or heel of which is journaled on a post 15^a erected on said base plate 15. To the free arm of said bell-crank lever 18 is pivotally connected one end of second lever 19, the opposite end of which is pivotally engaged by a second post 15^b erected on said base plate 15. Intermediate of the ends of said lever 19, there is pivotally connected thereto a thrust arm 20 extending therefrom in the direction of said pin 10 and provided near its opposite end with an anti-friction wheel 20^a adapted to bear against the periphery of a cam 21 keyed to said pin 10 above said table 16. The free end of said arm 20 is forked to engage said pin 10. A spring 22 is engaged at one end by said base plate 15 and at the opposite end by one of said levers, as by said bell-crank lever, for keeping said anti-friction wheel 20^a in constant pressure contact with said cam 21. It will be observed, therefore, that although said cam 21 does not rotate around said pin 10, it does rotate around the prolonged axis of shaft 7 and thus its greater and lesser diameters are successively presented to said anti-friction wheel 20^a resulting, when the greater diameter of said cam is so presented, in the oscillation of said table 16 in one direction, while when the lesser diameter of said cam is so presented, said spring 22 operates through the engaged levers to oscillate said table 16 in the opposite direction, the structure being such that the central 130

longitudinal axis of said table 16 and hand rest is kept in line with the central longitudinal axis of the student's right forearm as he makes the stroke.

5 When starting his stroke the swimmer's hand is assumed to be palm down; but after his arm has been extended forwardly full length and commences to make the lateral and backward sweep the palm should be 10 turned outwardly with the thumb side down. To effect this without muscular effort, I erect on said hand rest 17, a finger 17^a adapted at suitable times to be engaged by a cam 17^e, keyed to said pin 10, whereby said hand 15 rest is tilted on its side hinge 16^a during the outward and backward sweep of the arm of the student, said cam 17^e passing by said finger 17^a and permitting the free side of said hand rest to drop upon the lip 20 16^b during the retraction of the student's hand toward his shoulder and during the forward movement of his hand from a position near the shoulder to full arm forward position.

25 Mounted upon said frame in rear and above said arm and hand-operating mechanisms is a stationary bed or body support 23 of any suitable structure for supporting the body of the student in prone position, 30 upon which bed is mounted an adjustable head rest preferably comprising a pad 23^a secured to rods 23^b which rods are adapted to extend a greater or less distance into longitudinally directed apertures or recesses 35 formed in the frame of said bed. In rear of said bed is a flexible support 24 for supporting the student's legs, which support preferably consists of a broad strip of leather or textile material. The forward 40 end of said flexible support is secured to a transversely directed roller 24^a journaled upon said frame 1, which roller is provided at one end with a ratchet 24^b adapted to be engaged by a pawl 24^c mounted upon said 45 frame, whereby the operative length of said flexible support may be adjusted. The rearward end of said flexible support is secured to a spreader bar 25 extending transversely of said frame 1 and mounted at its opposite ends on carriages 25^a, 25^b adapted to move longitudinally of said frame 1 on stationary guides as 25^c secured to said frame. Depending from a carriage connecting bar 25^d are forks 26. Journaled on said frame 50 1 is a rock frame comprising a transversely directed rock shaft 27, posts 27^a, 27^b erected on said rock shaft, and a head bar 27^c mounted on said posts, said head bar being parallel to said rock shaft and to said spreader 55 and being closely straddled by said forks. In order to rock said rock frame, I provide the rock lever 5 rigidly secured to said rock shaft. Upon said rock lever is mounted an adjustable sleeve 5^a adapted to be fixed at a 60 greater or less elevation thereon by any suit-

able means as by a set screw 5^b. Pivots secured at one end to said sleeve is the connecting rod 4, the opposite end of which rod is journaled on the crank 3^b interposed in the power transmission shaft 3. It will 70 be observed that said rock frame operates to move said spreader toward or away from said bed, thus contracting or expanding said leg support longitudinally. Secured to said leg support at its rearward end are foot-holds of any suitable construction as straps 28 adapted to engage the ankles or feet of the student. Thus when the leg support is contracted the student will be forced to bend his legs at the knees, at the same time the 80 flexible support will be slackened, so that his knees can be depressed. When the leg support is expanded the student will be forced to straighten his legs and at the same time the flexible support will become taut 85 or flattened, thus continuing to give the legs proper support in their straightened position. It is also desirable that the student should part his knees when he bends his legs, to compel which, a forwardly projecting centrally positioned arm 29 is rigidly secured to said spreader below said flexible support. When said spreader moves forward to bend the student's legs, said flexible support sags down upon said arm 29 which 90 in a measure supports it along its longitudinal axis but permits it to drop lower at each side. The shallow, rounded ridge thus formed in said flexible support tends to part the student's knees.

100 It will be observed that said arm 8 is reciprocal and is adapted to yield in one direction to the pull exerted by the block 8^a and guide wheel 8^d in coöperation with the outer side of the track rail, and to yield 105 in the opposite direction to the pull at other moments of the block 8^b and guide wheel 8^e in coöperation with the inner side of the track rail, such latter pull being transmitted from said block 8^b to said arm 8 through 110 said tension springs 8^f. In Figs. 9, 10 and 12 are shown a modified form of track guided carriage and supporting arm and arm guide therefor, in which said guide comprises a bar 30 rigidly secured to said 115 shaft 7, and said carriage supporting arm comprises parallel reciprocal bars 31, 31^a engaging said guide at opposite sides, said bars being adjustably connected together by end pieces 31^b, 31^c. Mounted upon one end 120 of said arm is a carriage comprising a fork 32, in which is journaled a grooved guide wheel 33 adapted to bear upon the top of said rail 9 and engage both sides thereof. Formed on or secured to said fork is said 125 pin 10. In Figs. 13 and 14 is shown a modified form of said track comprising a grooved track rail 34 adapted to engage an overhead flangless guide wheel 35 journaled in said fork.

It is obvious that said structure and certain parts thereof may be further modified in various particulars within the scope and spirit of certain of my claims.

- 5 In operation, the student lies face down upon said bed, preferably resting his forehead upon said head rest, and is preferably secured to said bed by a belt to prevent slipping. The student lays his hands upon said hand rests within the loops of the hand retaining strips and his feet are secured by the foot straps at the spreader bar and the machine is then set in motion by said motor or by said hand crank 2^d, whereupon without special muscular effort or mental study the student's arms, hands and limbs will be forced by the apparatus through the movements suitable to the breast stroke style of swimming.
- 10 20 What I claim is—
1. The combination with a suitable frame, of a track supported on said frame near the forward end thereof, said track being positioned at one side of the central longitudinal axis of said frame, said track describing a course corresponding approximately to the course of movement of one of the hands of a swimmer in the breast-stroke style of swimming, a centrally positioned longitudinally extending stationary guide mounted upon the forward end of said frame near said track, a slidable block engaged by said longitudinal guide, a guide member or members carried by said block and extending across said longitudinal guide and over said track and over the area inclosed thereby, a rotatable shaft journaled on said frame and extending at right angles to the radial plane of said track and into the area inclosed thereby,
  - 15 30 35 40 45 50 55 60 65 means for rotating said shaft, a radially disposed arm carried by said shaft and adapted to extend over said track, a carriage mounted on said arm, track engaging means secured to said carriage and adapted to engage said track to hold said carriage at all times in position over the track rail, a fixed pin or post erected on said carriage, a guide follower mounted on said pin and adapted to engage said transversely directed guide member or members, said follower being adapted during its movement with said carriage along said track to cause said transverse guide member and its slidable block support to move back and forth along said longitudinally directed guide, a table journaled on said pin, a tiltable hand rest supported by said table at one end thereof, means including a cam formed on or keyed to said pin for tilting said hand rest at intervals, a slidable base mounted on said transverse guide, one end of said base being engaged by said pin, a second cam formed on or keyed to said pin, levers mounted on said slidable base and connected to said

70 75 80 85 90 95 100 105 110 115 120 125 130

ond cam to oscillate said table in one direction, means for retracting said levers to effect in part the oscillation of said table in the opposite direction when said second cam is out of operative position.

2. The combination with a suitable support, of a longitudinally extending body rest or bed, a reciprocable foot support in rear of said body rest, arm and hand operating means positioned forwardly of said body rest, said operating means being adapted to move the user's arms at his shoulders and elbows and to turn his hands pivotally at his wrists as in the act of breast stroke swimming, said foot support being adapted to bend and straighten the legs of a user as in the act of breast stroke swimming, and means for synchronously operating said arm operating means and foot support to cause the user to bend and straighten his legs and extend and retract his arms as in the act of breast-stroke swimming.

3. The combination with a suitable support, of a body rest or bed, longitudinally directed guides mounted on said support rearwardly of said bed, longitudinally movable carriages mounted on said guides, a transversely directed rod or bar adapted to be moved longitudinally of said support by said carriages, a flexible leg support in rear of said bed, said leg support being secured at its end farthest from said bed to said transverse bar, and means for moving said carriages back and forth along said guides.

4. The combination with a suitable support, of a body rest or bed mounted thereon and adapted to sustain the body of the user, a longitudinally directed centrally positioned stationary guide mounted on said support forward of said bed, a track mounted on said support at the left of said longitudinal guide, said track describing a course corresponding approximately to the course of movement of a swimmer's left hand in swimming in breast-stroke style, a track mounted on said support at the right of said longitudinal guide, the latter track describing a course corresponding approximately to the course of movement of a swimmer's right hand when swimming in breast-stroke style, a left hand rest, means for supporting said left hand rest above said left track and for swinging said left hand rest in a course parallel and concentric to said left track in a direction opposite to the normal direction of movement of clock hands, a right hand rest, means for supporting said right hand rest above said right track and for swinging said right hand rest in a course parallel and concentric to said right track in a direction similar to the normal direction of movement of clock hands, means for oscillating said hand rests during their progress so as to keep their longitudinal axes directed toward said bed, a movable foot support mounted on

said frame rearwardly of said bed, and means for moving foot support toward and away from said bed.

- 5 5. The combination with a suitable frame of tracks mounted upon the forward end thereof at opposite sides respectively of the longitudinal axis of said frame, hand rests positioned adjacent to said tracks respectively, means for supporting one of said hand 10 rests, said means being adapted in coöperation with the respectively adjacent track to swing said hand rest in a course parallel to said track, means for supporting the other of said hand rests, the latter said means being adapted to swing said other hand rest in a course parallel to the respectively adjacent said track, and means for tilting said hand rests during a portion of their swinging movement.
- 15 20 6. The combination with a suitable frame, of a body support mounted thereon; arm governing means mounted upon said frame forward of said body support, said means being adapted to engage the user's hands 25 and extend, diverge, flex and retract his arms as in the act of breast-stroke swimming; leg governing means comprising a transversely directed adjustable support mounted on

said frame in rear of said body support, a rearwardly extending flexible leg support 30 secured at its forward end to said adjustable support, a reciprocable support for the rearward end of said flexible support, means including a rock frame for reciprocating said reciprocable support longitudinally of said 35 frame toward and away from said body support, said flexible support being adapted to sag downwardly when said reciprocable support is moved toward said body support, means carried by said reciprocable support 40 and extending beneath said flexible support for limiting the sag of said flexible support along its longitudinal axis for part of its length, means for securing the feet of the user at the rearward end of said flexible support; and means common to said leg governing means and to said arm governing means 45 synchronously.

In testimony whereof, I hereunto affix my signature, in presence of two witnesses.

ALFRED E. WATTS.
